UNITED STATES PATENT OFFICE.

HENRY C. KARPEN, OF BROOKLYN, NEW YORK.

DESIGN FOR A WATCH-CHARM OR SIMILAR ARTICLE.

51,985.

Specification for Design.

Patented Apr. 23, 1918.

Application filed November 5, 1917. Serial No. 200,448. Term of patent 14 years.

To all whom it may concern:

Be it known that I, HENRY C. KARPEN, a citizen of the United States, and a resident of the city of New York, borough of Brooklyn, in the county of Kings and State of New York, have invented a new, original, and ornamental Design for a Watch-Charms or Similar Article, of which the following is a specification, reference being had to the

accompanying drawing, forming part thereof, in which—

The figure is a perspective view of an article shaped in conformity with the herein disclosed design.

I claim:

The ornamental design for a watch charm or similar article, as shown.

HENRY C. KARPEN.
